UNITED STATES PATENT OFFICE

CHARLES A. OLSON, OF GENEVA, ILLINOIS, ASSIGNOR TO CRANE CO., OF CHICAGO,
ILLINOIS, A CORPORATION OF ILLINOIS

BOILER

Application filed May 3, 1929. Serial No. 360,055.

This invention relates in general to steam and hot water boilers and particularly to sectional boilers having vertically extending sections. This novel construction of water chamber and flue passages has been evolved to make possible greater efficiency in boiler operation and to make available new advantages and conveniences in the manufacturing of the equipment.

10 The construction which is herewith described and shown illustrates one embodiment of the invention and is similar to the construction shown in my prior application Serial No. 314,972, filed October 25, 1928, differing however therefrom in respect to the construction of the rearmost vertical section.

The rear section herein described is an improvement over the rear section shown in said prior application and provides new advantages in the manufacturing of the said section, in the maintenance of the section during use and in the efficiency with which the heat is transferred from the flue gases to the water contained within this section.

25 One of the objects of this invention is to provide a boiler section having an upright water leg and an enlarged water chamber thereabove extending more or less horizontally therefrom, both of which have surfaces

30 against which the products of combustion directly impinge and which surfaces are constructed to withstand extremely high flue gas temperatures and to expand and contract under changing temperatures without de-
structive stresses being set up therein.

Another object of this invention is to provide a boiler section capable of attaining the above objects and also adapted for convenience in casting and so designed as to eliminate destructive stresses therein during the casting thereof.

Another object of this invention is to provide a vertical boiler section adapted to be disposed at one end of a fire box having a water leg and a vertical wall capable of

flexing without destructive stresses under the influence of high fire box temperatures and having connected thereto an enlarged water chamber extending inwardly over the combustion space of the fire box provided with a heat transfer surface connected to said vertical wall in a manner permitting unequal expansion and contraction of said surface and said wall without disruptive stresses at the conjunction of said surface and wall.

Other objects and advantages inherently possessed by this invention will later become apparent upon a perusal of this specification.

Fig. 1 of the drawings is a front elevation of the second vertical boiler section shown in Fig. 2 counting from the left thereof.

Fig. 2 is a vertical longitudinal section through the middle of the boiler.

Fig. 3 is a front elevation of the rear boiler section.

Fig. 4 is a section on a horizontal plane passing through the line 4—4 of Fig. 3.

Fig. 5 is a partial rear elevation of the rear boiler section.

It should be understood that the number 70 of vertical boiler sections which may be used in forming a single boiler is subject to variation and that the four herein shown serve only to illustrate the invention.

Referring to Fig. 2 the front section is 75 designated as 1, the first intermediate section as 2, the next intermediate section as 3 and the rear section as 4. The intermediate boiler section shown in Fig. 1 illustrates the arrangement of water chamber and flue passages which are preferably employed in all the intermediate sections, the two intermediate sections herein shown being identical except for the provision of a steam or water outlet on the top of section 2.

The fire box generally indicated as 5 extending above the saddles 6 on which the grate bars may be mounted will contain the fuel and the products of combustion arising therefrom.

The products of combustion flow as follows. The burning gases impinge against the side walls 7 of the water legs 8 of the intermediate sections. The products of combustion at the top of the fire box will likewise impinge against the inclined surfaces 9 and 11 of these intermediate sections and will then flow rearwardly toward the rear boiler section. As these gases strike the rear wall 12 of the rear boiler section and particularly its upper portion 13 they will be deflected upwardly against the ledge 14 and will then enter the pair of horizontal flue passages 15 and 16 which the vertical section 3 will have corresponding to the like designated passages in Fig. 1. The forward flow of these gases through the passages 15 and 16 is indicated by the dotted arrows in Fig. 2. As the gases emerge from the vertical section 2 into the front section 1 part of them will continue to flow through passages in the front section corresponding to the passages 15 and 16 of Fig. 1 but some of the gases will rise directly through the flue chamber 17 and flow directly back through the upper horizontal flue passage. The flue gases which continue to flow forwardly toward the twin lower horizontal flue passages in the flue section will rise, as indicated by the arrows, upwardly past an opening 18 which will be covered by a flue cleanout door, not shown, and will then flow rearwardly through a common continuous upper horizontal flue passage formed by the joining of the passages 19, 20, 21, and 22 of the adjoining boiler sections. The general shape of this upper horizontal flue passage corresponds to that which is shown in Fig. 1. The flue gases emerging from the rear boiler section then will pass out into a smoke box, not shown, but which can be attached conveniently to the lugs 23 shown in Fig. 5. Note that the flue gases are caused to flow rearwardly in the fire box until they reach the back water leg of the rear boiler section then flow forwardly through the twin lower flue passages 15 and 16 all the way to the front of the boiler, then rise and flow rearwardly again the entire length of the boiler before passing out into the smoke box. This arrangement gives an unusually long distance of travel of the flue gases in a boiler of this type and is found to afford the heat transfer surfaces sufficient opportunity to absorb an exceptionally high percentage of the heat contained in these gases.

Each of the boiler sections is provided with vertical water legs at the side of the combustion space similar to the water legs 8 shown in Fig. 1. The water is admitted into the boiler preferably at the rear thereof through a water inlet 24 on each side of the rear boiler section. The water flows forwardly from the bottom of each lateral water leg into the bottom of the lateral water legs in

each adjoining section through connecting passages similar to the passage 25 shown in Fig. 2. The registering ports in the adjoining water legs which provide communication between the bottoms of these water legs are provided with push nipples 26 which establish a tight seal when the sections are drawn together by means of horizontal tie rods, not shown, passing through the lugs 27 provided on the rear section and similar lugs on the front boiler section, two of these lugs 28 being shown on the front section in Fig. 2.

In the front boiler section a water leg is also provided at the front side thereof which must of course pass around the cleanout door opening 29 and the fire box door opening 31. Portions of this front water leg are indicated at 32 and 33.

It is an object of this invention to connect the water legs in the front section and all of the intermediate sections to the upper water passages in the manner similar to that shown in Fig. 1. As the hottest of the products of combustion are normally directly above the fire and as they will naturally rise to the upper limit of the fire box water passages 34 and 35 upwardly inclined toward the center line of the fire box are provided in the intermediate sections and similarly in the front section. The high temperature which the heat transfer surfaces 9 and 11 attain will naturally cause rapid transmission of heat to the water in the passages lying above them and will induce a rapid flow of the water from the water legs across these surfaces toward the middle of the boiler thence upwardly through a common vertical water passage 36 thence outwardly and upwardly through connected water passages 37 and 38. As the water emerges from these latter two passages it then rises through the outside vertical passages 39 and 41 and enters the common water chamber 42 which lies above the uppermost flue passage 20. This common water chamber is indicated in Fig. 2 by the numerals 42 and 42' in the several boiler sections.

When this boiler is used for the generation of steam the water level will preferably be maintained at about the position shown by the line 43 in Fig. 1. Since this water level is slightly below the passages 44 which connect the steam spaces in the several sections it is evident that even when the boiler is producing steam at a rapid rate the steam rising from the surface of the water in the several sections will have ample time to lose the excess of moisture in the form of water particles which it may carry before it passes out through either or both of the steam outlets 45 and 46, either of which or both of which may be used as desired. These passages are sealed by push nipples 47 held in sealing contact with the sections by the compression afforded by the aforementioned tie rods. The

ports 48 and 49 shown in the front and rear boiler sections, respectively, may be closed by plugs or may be utilized as desired for the attachment of instruments or other connections.

In order to assist in inducing the water rising from the lateral water legs to flow inwardly and upwardly toward the central water passage 36 there are provided deflecting baffles 51 and 52 as shown in Fig. 1. These baffles deflect water toward the central water passage 36 yet do not prevent water from flowing through the vertical water passages 53 and 54. Some downward flow of water through the passages 53 and 54, when a cold boiler is being heated, will assist materially in initiating and quickening the circulation of water in the water passages while a small amount of upward flow which may occur during the operation of the boiler will assist in the efficient transfer of heat from the flue gases to the water.

Referring now particularly to the rear boiler section it is to be noted that the ledge 14 is inclined at a substantial angle to the vertical wall of the back water leg making possible the use of an amply large fillet 55. The manner of joining the ledge 14 with the vertical wall 13 is such that, under the fluctuating temperatures which strike these heat transfer surfaces and which may vary from the maximum fire box temperature obtainable in the boiler to a relatively low temperature when the fire is banked, it permits the expansion and contraction of these surfaces, which may or may not proceed equally, to occur without setting up destructive stresses which might cause cracking of the casting at or near the fillet 55. If this fillet were sharper and the two joined surfaces disposed approximately at right angles to each other the expansion and contraction of these surfaces might cause the casting to crack when the boiler is being used. Furthermore, it has been found that the construction of the rear boiler section as shown in Fig. 2 lessens the danger of the casting cracking in the foundry when it is being made.

Not only does the novel construction of this rear boiler section eliminate cracking during casting or during the operation of the boiler but it also, by reason of the inclination of the ledge 14 above the high temperature flue gases, induces a rapid upward flow of water from the depending water legs across this very efficient heat transfer surface thence upwardly and around the flue passage 22 up toward the steam space. Note that Fig. 3 indicates that the water passage lying above the ledge 14 is formed in two upwardly and outwardly inclined passages 56 and 57 which carry the water around the lateral extremities of the upper flue passage 22. These upwardly and outwardly inclined passages meet at their lowermost point at the longitudi-

dinal middle of the fire box where normally the hottest products of combustion will strike the underside of the ledge 14. Also these hottest gases will strike the vertical wall 13 at its middle portion. Due to the higher gas temperatures which are applied to this part of the heat transfer surface the more rapid conduction of heat to the water at these points will cause a more rapid flow of water upwardly from the back water leg upwardly and forwardly over the ledge 14 thence outwardly and upwardly through the passages 56 and 57. This rapid flow of water over these more highly heated heat transfer surfaces will promote the efficiency with which the heat units of the fuel are transferred to the water. The higher temperatures attained on these surfaces and the more rapid circulation of water over them thus increasing the efficiency of the boiler operation are operative advantages which reside in this construction along with the structural advantages previously mentioned which eliminate destructive stresses.

The front wall of the rear water leg in the rear boiler section is also corrugated as indicated in Figs. 2, 3 and 4, which also permits of contraction and expansion of this wall without destructive consequences. The corrugated front wall of the rear water leg cooperates with the inclined surface of the ledge 14 during the expansion and contraction of these surfaces. Both surfaces, being somewhat resilient, are capable of the slight amount of relative movement which may be caused by unequal temperature variations. The resiliency of the corrugated surface and the ledge 14 and their connection at the curved fillet 55 also enables them to cool and contract during the casting of the rear section without the occurrence of destructive stresses which might result in cracking of the casting. Also the corrugations increase the amount of heat transfer surface which may be available between the lateral extremities of the boiler section.

The drawings and the specification illustrate but one embodiment of this invention. It should be understood that other embodiments and modifications of the invention may be devised which will yet remain within the spirit and scope of this invention as defined in the claims which follow.

I claim:

1. In a boiler having a flue communicating with the fire box and extending generally horizontally, a water chamber comprising an upright water leg at one margin of the boiler fire box and a water passage joined to the top of said leg extending inwardly over the fire box having as its lower wall an inclined surface arranged to deflect the products of combustion from the fire box upwardly into said flue, said surface having its lowermost portion joined to the upper middle portion of the

inner wall of said water leg on which lowermost portion the hottest of the products of combustion strike as they are being deflected into said flue, said inclined surface being designed to rise inwardly, laterally and upwardly from its said lowermost portion, said arrangement of the inclined surface of said water passage and the connection of the latter with said water leg being adapted to aid a rapid flow of water over the most highly heated portion of said surface.

2. In a boiler having a flue communicating with the fire box and extending generally horizontally, a water chamber having a depending water leg disposed at a margin of the boiler fire box and an inwardly projecting water passage extending inwardly over the fire box from the upper end of said water leg and in communication therewith, the bottom of said passage being substantially inclined and having a depressed middle portion connected to the inner wall of said water leg by a curved fillet, the portions of said water passage on either side of its depressed middle portion being upwardly inclined at a substantial angle, the whole being arranged to permit a heat-induced rapid circulation of water from the middle of the water leg through the middle of the projecting portion of said water passage.

3. In a vertical sectional boiler, a plurality of vertical boiler sections adapted when assembled to provide a generally horizontal flue passage communicating with the top of the boiler fire box, and a vertical boiler section having a depending water leg disposed at one margin of the boiler fire box near the entering end of said flue and having an inwardly projecting water chamber at the top of its water leg, the bottom surface of said water chamber being inclined laterally inwardly and upwardly at a substantial angle and arranged to deflect the products of combustion rising in said fire box into the entering end of said flue, the bottom of said water chamber being joined by a curved fillet to the inner wall of said water leg, the ceiling of said water chamber forming the bottom of a second flue passage and being inclined from its middle portion upwardly toward its lateral margins to encourage the flow of water from the middle portion toward the opposite lateral portions of said chamber.

4. In a vertical sectional boiler, a plurality of vertical boiler sections adapted when assembled to provide a generally horizontal flue passage communicating with the top of the boiler fire box, and a vertical boiler section having a depending water leg disposed at one margin of the boiler fire box near the entering end of said flue and having an inwardly projecting water chamber at the top of its water leg, the bottom surface of said water chamber being inclined inwardly and upwardly at a substantial angle and ar-

ranged to deflect the products of combustion rising in said fire box into the entering end of said flue, the bottom of said water chamber being joined by a curved fillet to the inner wall of said water leg, the middle portion of said water chamber being depressed relatively to its lateral portions.

In witness of the foregoing I affix my signature.
